UNITED STATES PATENT OFFICE

GOLDER E. STEVENS, OF SEMINOLE, OKLAHOMA

DILATING IRRIGATOR

Application filed September 26, 1929. Serial No. 395,383.

This invention relates to a surgical instrument which is mainly designed for the treatment of gonorrhoea, but which, of course, can be used for other purposes, the general object of the invention being to provide means for dilating the walls of the passage to be treated so that the fluid or the like introduced through the instrument will come in full contact with all portions of the diseased parts.

Another object of the invention is to provide a head on the inner end of the instrument which is so shaped as to facilitate the entrance of a part of the instrument in the part to be treated, said head also acting as a stop for preventing the fluid from passing beyond the diseased parts, which would act to carry germs to the parts not diseased.

A further object of the invention is to provide means whereby the fluid can be caused to circulate through the instrument to irrigate the diseased parts or can be held in contact with the diseased parts for any desired length of time.

Another object of the invention is to provide means whereby the expandable part of the instrument can be expanded or contracted from that end of the instrument which is exterior of that part of the body being treated.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a longitudinal sectional view showing the expandable part of the instrument contracted.

Figure 2 is a similar view but showing said part expanded.

Figure 3 is an enlarged elevation of the inner end of the device.

Figure 4 is a section on line 4—4 of Figure 3.

In these views, the numeral 1 indicates the outer tube which is formed with a downwardly curved front end 2 containing a valve 3, and the numeral 4 indicates a perforated collar arranged in the inner end of the tube 1. The inner tube is shown at 5 and has a threaded outer part which passes through a bushing 6 on the outer end of the tube 1 and said tube 5 passes through the tube 1 and through the collar and projects a considerable distance beyond the inner end of the tube 1. A substantially conical shaped head 7 is connected with the inner end of the tube 5 and is of hollow construction so that liquid or the like passing through the tube 5 will flow into the head and then pass therefrom through the perforations 8 which direct the liquid toward the inner end of the tube 1. Spring strips 9 have their ends connected with the inner end of the tube 1 and the head and these strips are so formed that when the tube 5 is moved outwardly to draw the head toward the tube 1, the strips will assume a bowed shape, as shown in Figure 2, so that they will expand or dilate the walls of a passage in which this part of the device is located. A nut 13 is placed on the threaded part of the tube 5 and by turning this nut to cause it to press against the end of the bushing, the tube 5 will be moved outwardly and thus the spring strips will be expanded. When the nut is turned in the opposite direction, the spring strips and the pressure thereon of the dilated walls of the passage will move the inner tube to normal position, with the spring strips contracted.

The outer end of the tube 5 is of substantially funnel shape, as shown at 10, so that the tapered nozzle 11 of a bulb or syringe 12 can be inserted therein to force liquid through the tube 5.

From the foregoing it will be seen that the instrument can be inserted in a passage in the human body to a point where the expandable part thereof formed by the strips 9 will come opposite the parts to be treated. Then by turning the nut 13, the strips will be expanded so as to dilate the walls of that por-

tion of the passage to be treated. Then the liquid is forced through the tube 5 so that it will enter the head and flow backwards through the passage 8 into the dilated part 5 of the passage to be treated, after which the liquid will flow through the perforations in the collar 4 and through the tube 1, past the valve 3 to the point of discharge. Thus the liquid comes in full contact with all parts of 10 the diseased walls and by opening the valve 3, the parts can be irrigated as long as desired. By closing the valve, the liquid can be held in contact with the diseased walls as long as desired. After the treatment is finished, the nut is turned in an opposite direction so as to straighten the strips 9 and thus permit the instrument to be removed.

Attention is called to the fact that the head 7 not only acts to facilitate the entrance of 20 the instrument into a passage, but it also acts as a stop for preventing the liquid from passing beyond the diseased parts. Thus there is no danger of the liquid carrying the germs to parts which are not diseased. As the liquid flows back into the tube 1, after leaving the diseased parts, the forward part of the passage is also protected from the liquid carrying the germs.

As before stated, the instrument is mainly 30 designed for treating gonorrhœa, especially in males, but, of course, it can be used for other purposes.

It is thought from the foregoing description that the advantages and novel features 35 of the invention will be readily apparent.

It is to be understood that changes may be made in the construction and in the combination and arrangement of the several parts, provided that such changes fall within the 40 scope of the appended claim.

What I claim is:—

A dilating irrigator comprising a L-shaped tube, one branch thereof forming a combined handle and discharge portion and the other 45 branch providing a comparatively long syringe portion to be inserted in a passage of a person, a control valve in the combined handle and discharge portion, a perforated disk located in the free end of the syringe 50 portion and having a centrally arranged bearing opening, a bushing formed on the tube at the bend thereof and having the bore of said bushing in alignment with the bearing opening, a second tube slidable in the 55 bushing and bearing opening and having one end flared to receive a syringe, a hollow conical-shaped head formed on the other end of the second tube and having discharge openings directed toward the perforated disk, flexible strips connected to the head and to the free end of the syringe portion to be flexed by the movement of the head relative to the free end of the syringe portion, and a 60 nut threaded to the second tube and bearing against the bushing for varying the head 65 ing against the bushing for varying the head

relative to the free end of the syringe portion and to expand the walls of the passage adjacent the head by flexing the strips.

In testimony whereof I affix my signature.
